(57) **CLAIM**

The ornamental design for a foldable mirror, as shown and described.

DESCRIPTION

FIG. 1 is a front, right, and top perspective view of a foldable mirror, showing my design, wherein mirrors of the foldable mirror are folded.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is front, right, and top perspective view of the foldable mirror of FIG. 1, wherein the mirrors are unfolded. The broken lines shown in the drawings illustrate portions of the foldable mirror that form no part of the claimed design.
